(57) **CLAIM**

The ornamental design for a medical wash basin with sliding cover, as shown and described.

DESCRIPTION

FIG. 1 is a front elevational view of the medical wash basin with sliding cover of the present invention;

FIG. 2 is a rear elevational view of the medical wash basin with sliding cover of FIG. 1;

FIG. 3 is a right side elevational view of the medical wash basin with sliding cover of FIG. 1;

FIG. 4 is a left side elevational view of the medical wash basin with sliding cover of FIG. 1;

FIG. 5 is a top plan view of the medical wash basin with sliding cover of FIG. 1;

FIG. 6 is a bottom plan view of the medical wash basin with sliding cover of FIG. 1;

FIG. 7 is a top, front, right side perspective view in an alternate position (slide cover moved to right); and,

FIG. 8 is a cross-sectional view of FIG. 4 taken along line 8—8.
